Inventor:

JOHN T. DRUFVA,
By his Attorney,

Charles C. Gill.

UNITED STATES PATENT OFFICE.

JOHN T. DRUFVA, OF LONG MEADOW, MASSACHUSETTS, ASSIGNOR TO HENRY HYMAN & CO., INC., OF NEW YORK, N. Y., A CORPORATION OF NEW YORK.

DESIGN FOR A CONTACT DEVICE FOR PORTABLE ELECTRIC LIGHTS.

58,894.

Specification for Design.

Patented Sept. 6, 1921.

Application filed January 14, 1920. Serial No. 351,481. Term of patent 14 years.

To all whom it may concern:

Be it known that I, JOHN T. DRUFVA, a citizen of the United States, residing at Long Meadow, in the county of Hampden and State of Massachusetts, have invented a new, original, and ornamental Design for a Contact Device for Portable Electric Lights, of which the following is a specification, reference being had to the accompanying drawings, forming a part thereof, and in which—

Figure 1 is a front view,

Fig. 2 an edge view, and

Fig. 3 an upper end view of a contact device for portable electric lights embodying my design.

I claim:

The ornamental design for a contact device for portable electric lights, as shown.

JOHN T. DRUFVA.
